CLEANER AND HULL EXTRACTING FEEDER
FOR COTTONFrank E. Deems, Birmingham, Ala., assignor to
Continental Gin Company, a corporation of
Delaware

Application July 15, 1935, Serial No. 31,371

10 Claims. (Cl. 19—37)

My invention relates to a cleaner and hull extracting feeder wherein the seed cotton can be passed either directly to an extractor and thence to an after-cleaner, or can be shunted about the extractor and delivered directly to the after-cleaner.

One object of my invention is to design an apparatus of this character which is very compact in arrangement and is so designed that it can be interposed readily within the standard clearance provided between the gin stands and their distributors in existing ginning plants.

My invention further contemplates arranging for a lateral delivery of the entering seed cotton into contact with the upwardly moving face of an extractor cylinder which is housed in a vertical extension of the cleaner casing rising alongside the distributor chute, thereby setting the extractor mechanism to one side and partially above the low level of the chute.

My invention further contemplates the provision of a picker roll adapted to pass the entering cotton over a screen door on the intake side of the feed hopper so that the dirt and trash screened out of the cotton stream may pass directly to an underlying hull and trash outlet, said door being adapted to be opened when the cotton stream is to be passed directly to the after-cleaner rolls.

My invention further contemplates the provision of a hull chute leading downwardly from the extractor cylinder across the cleaner casing and over the after-cleaner compartment, the chute having its discharge edge upturned in accordance with the disclosure in the patent to Elliott, No. 1,880,934, so that a reclamer cylinder can work in the bend of this hull chute to effectively recapture cotton tending to pass off with the hulls and return it to the cotton stream passing to the extractor cylinder.

My invention further contemplates providing a hopper bottom for delivering all hulls and trash to a common conveyor, this hopper bottom being overhung throughout by the screen bottom of the after-cleaner chamber and the screen door of the feed hopper and therefore adapted to receive hulls and trash across the full width of the cleaner.

My invention further comprises the novel details of construction and arrangements of parts which in their preferred embodiment only are illustrated in the accompanying drawing, which shows in conventional manner a vertical cross section of my improved cleaner and hull extracting feeder with its drive mechanism omitted, as same can be of any suitable character to rotate

its parts in the direction indicated on the drawing.

I show conventionally a distributor 1 having a bottom discharge chute 2 for delivering seed cotton into the feed hopper 3 of the cleaner mechanism where the feeder rolls 4 deliver the cotton in a stream between them into position to be engaged by the initial picker roll 5 rotating counter-clockwise and thrown against a screen door 6, closing the intake side of the feed hopper, to open the cotton and partly clean it, and then to pass it through the opening 7 into engagement with a second picker roll 8 rotating clockwise by which it is carried under the hull board 9 and thrown against the up-going side of a toothed cylinder 10. 15

Ample clearance is provided between the hull board 9 and the cylinder 10 so that there will be no tendency for the cotton to choke in the chamber 11 formed in a vertical extension 12 of the main cleaner casing 13. This extension lies alongside the distributor chute 2 and in it is mounted the stripper roll 14 rotating clockwise and the baffle 15. These elements coact in the usual manner to strip the hulls and loose trash back from the cotton stream on the saw cylinder 18 onto the hull board 9 down which the hulls work their way and fall through the cotton stream onto an inclined hull chute 16 leading inwardly and downwardly from close proximity to the cylinder 10. 25

This hull chute 16 comprises at its lower end a hinged trough-like member 17 which passes with a reasonably close clearance under a small saw cylinder 18 driven clockwise so that its under face has the same direction of travel as the hulls. This trough member 17 is adapted to bring cotton tending to pass off with the hulls into position to be picked up by the saw cylinder 18 and carried upwardly under a baffle 19 that extends downwardly from the feed hopper into close proximity to the cylinder 18 so that it will act to strip hulls from the cotton engaged by cylinder 18. Beyond this baffle is a doffer 20 rotating counter-clockwise to remove the cotton from the cylinder 18 and pass it upwardly between the baffles 21 and 22 into position to be engaged by the picker roll 8 and restored to the cotton stream on its way to the cylinder 10. 40

The trough element 17, in accordance with the principles of construction and operation fully described and claimed in the Elliott Patent No. 1,880,934, can be adjusted to raise and lower its discharge edge and to control the working clearance under the saw cylinder 18. This cylinder 18 on its upgoing side acts to discharge the hulls tending to accumulate between it and the dis- 55

charge end of the element 17 so that they will fall onto a door 23 which is normally in closed position in which it engages the flange 24 under the chute member 17 and in such position it acts to 5 deflect the hulls, together with any trash falling thereon through the screen door 6, into a chute 25 leading to the trough 26 in which a screw conveyor 27 works.

I provide a main doffing roll 28 rotated counter-clockwise and adapted to remove the stripped cotton stream from the cylinder 10 and deliver it into what I term the after-cleaner chamber 29, which extends inwardly across the mechanism and along under the chute elements 16, 17 which 10 form a top cover therefor. A series of picker rollers 30, 31 and 32 are arranged in the chamber 29 and all driven counter-clockwise so that the cotton stream doffed thereinto is carried downwardly across the after-cleaner chamber to the 15 normally closed door 23 which causes it to return over the screen bottom 33 of this after-cleaner chamber to the doffer 28 and to be discharged thereby into the outlet 34 whence it passes over a chute 35 to the cotton inlet in the gin breast 36.

25 An inclined hopper wall 37 extends from the delivery end of the screen bottom 33 and merges into the chute 26. Thus the hopper bottom extends the full working width of the cleaner and, with the parts in the position above described, it underlies the screen elements 6 and 33 which taken together also extend the full transverse width of the apparatus, thus giving the maximum cleaning space for the removal of dirt or trash from the cotton stream.

30 When it is desired to cut the extractor mechanism out of service, the screen door 6 of the feed hopper is swung about its pivotal bearing 38 into the dotted position shown, and the door 23 at the inner end of the after-cleaner chamber 29 is moved about on its pivot 39 to the dotted position shown when it rests in engagement with the hull chute wall 40. This door 23 will in this position intercept the direct passage of any material from the feed hopper 3 into the chute 25 and at 35 the same time the picker roll 5 will deliver the entire stream of entering cotton, with any accompanying hulls and trash, downwardly into the casing and onto the door 23 down which it will slide into engagement with the inner after-cleaner roll 32. This roll and the succeeding after-cleaner rolls will pass the cotton stream over the screen bed 33 to the doffer roll 28 which 40 will discharge it in the manner described.

45 The operation of my invention will, from the foregoing description, be readily understood. When cotton is of a character requiring treatment both by the after-cleaner and the extractor mechanism, the parts will occupy the full line position shown and the main cotton stream will be driven under roll 5, over roll 8 onto cylinder 10, and after being stripped by the roll 14 and doffed by the doffer 28, will pass over the series of after-cleaner rolls to the inner end of the after-cleaner 50 29 and then return under the rolls over the screen bed 33 and be discharged.

55 The hulls and trash removed in the extractor will slide down the chute elements 16 and 17 and be delivered into the hull chute 25 where they will mingle with trash and hull particles falling through the screen 6, and thus all dirt, hulls and trash falling through the screen bed 33 and screen 6 will collect in the chute 26 and be discharged together by the screw conveyor 27. The cotton re-claimed from the hulls by the saw cylinder 18 will 60 be doffed by the doffer 20 and returned by roll 65

70 8 into the cotton stream approaching the cylinder 10.

75 Whenever the cotton is sufficiently clean not to require treatment by the extractor, the door 6 is opened in the hopper 3 and door 23 is opened 5 in the after-cleaner chamber, whereupon the cotton stream will pass directly to the after-cleaner rolls and, after receiving the usual cleaning treatment from them, will be delivered directly to the gin without coming in contact with 10 any of the extractor elements.

15 This apparatus is very compact, there is no waste space in it and the clearance normally existing between the gin and distributor is ample to receive this combination hull extractor and 20 cleaner feeder mechanism.

25 While I have shown my invention in but one form, it will be obvious to those skilled in the art that it is not so limited, but is susceptible of various changes and modifications, without departing 30 from the spirit thereof, and I desire, therefore, that only such limitations shall be placed thereupon as are imposed by the prior art or as are specifically set forth in the appended claims.

What I claim is:—

1. In combination, a cleaning and hull extracting feeder, comprising a casing having a feed hopper containing a picker roll and having a side extractor outlet and a door, a hull extractor mechanism comprising a saw with its 30 upgoing side opposite said outlet, a stripper and hull board arranged above said outlet and a doffer and hull chute arranged below said outlet, means to reclaim and return to said saw cotton tending to pass off said chute with the 35 hulls, a screen bed spaced below said hull chute to form a cleaner chamber having said doffer at one end, a gate valve at the other end of said chamber, a series of cleaner rolls working over said screen bed, and a hull discharge, said valve 40 in one position acting to admit hulls from said chute to said discharge and in another position to admit cotton falling from said hopper when its door is open into the inner end of said cleaner chamber for treatment therein. 45

2. A cleaner feeder according to claim 1, in which the gate valve underlies said door in the feed hopper.

3. A cleaner feeder according to claim 1, in which the hull discharge underlies said door in the feed hopper and is formed in part by one of the bottom casing walls which converges towards a screw conveyor and directs thereto both the hulls and the matter falling through said screen bed. 55

4. A cleaner feeder according to claim 1, in which the casing feed hopper underlies a distributor chute and the casing over the hull extractor mechanism is offset from and rises above the bottom level of the distributor chute. 60

5. In combination, a cleaner feeder comprising a casing having a feed hopper containing a picker roll and having a side extractor outlet and a bottom cleaner outlet with a screen door for closing the latter outlet, a hull extractor mechanism at the side of said hopper comprising a main saw opposite said extractor outlet with its cotton receiving surface traveling upwardly, a stripper roll and hull board above said side outlet, a doffer, a hull guide leading inwardly from said saw, a reclaiming saw working over said hull guide to re-capture cotton escaping with the hulls down said guide, and means to return cotton from said reclaiming saw to said main saw, a screen bed forming with said hull guide a transverse clean- 75

ing chamber with said doffer at its outer end, a gate valve at its inner end and a series of cleaning rolls interposed, the gate valve in closed position acting to open a hull discharge passage and in its open position to direct cotton from said cotton cleaner outlet of the feed hopper into the inner end of said cleaner chamber for treatment therein.

6. In combination, a cleaner feeder having a feed hopper with a picker roll and a side extractor outlet and a screen door on its intake side controlling a cleaner outlet, a hull extractor assembly comprising a main saw opposite said side outlet of said hopper, a reclaiming saw below the hopper, a guide for conducting hulls from the extractor under said reclaiming saw for treatment thereby, and a doffer for the main saw, a series of cleaning rolls placed to receive the doffed cotton and working over a screen that forms with said hull guide a cleaning chamber, means to return to the main saw cotton caught by said reclaiming saw, a gate valve closing the inner end of said cleaning chamber and adapted when open to receive cotton from said cleaner outlet of said feed hopper and deliver it into the inner end of said cleaning chamber, the hulls being normally discharged from said guide past said closed gate into a bottom hull discharge means.

7. In combination, a casing having a cotton inlet and a cotton discharge, a hull extractor mechanism on the cotton discharge side of the casing, an after-cleaner compartment disposed across the casing in position to deliver cotton into said discharge and comprising a series of cleaner rolls and a bottom screen bed, means to deliver the cotton stream directly from said inlet into the inner end of said after-cleaner compartment for a single traverse thereof to the cotton discharge, and means to deliver the cotton

stream from said extractor mechanism into the outer end of said compartment in position to engage said cleaner rolls and be driven thereby for a double traverse of said compartment in its passage to said discharge, and means to discharge the hulls and trash removed from the cotton stream in its selected traverse of said casing. 5

8. In a machine as described in claim 7, the hull extractor mechanism comprising an extractor saw and doffer positioned in the outer or discharge end of the after-cleaner compartment. 10

9. In a machine as described in claim 7, the hull extractor mechanism comprising an extractor saw and doffer positioned in the outer or discharge end of the after-cleaner compartment with the doffer working over said screen bed and forming part of the after-cleaner mechanism. 15

10. In combination, a casing having a cotton inlet and a cotton discharge, a hull extractor mechanism comprising a doffer and extractor saw, an after-cleaner compartment disposed across the casing in position to deliver cotton into said discharge and comprising at its inner end a gate and having at its outer end said doffer, and an interposed series of cleaner rolls between said gate and doffer with a screen bottom under said rolls and doffer, means to divert a cotton stream through said gate into the inner end of said after-cleaner compartment for a single traverse thereof, means to direct the cotton stream to the extractor mechanism, with the doffer adapted to direct the cotton stream in a double pass into the outer end of said after-cleaner compartment, and means to discharge the hulls and trash removed from the cotton stream in its traverse of the casing. 20 25 30 35
